WAISTLINE CONTROL GARMENT

Louis Shulman, New York, N. Y.

Application July 10, 1946, Serial No. 682,565

2 Claims. (Cl. 2—43)

1

This invention relates to new and useful improvements in a waistline control garment.

The invention contemplates the correction and improvements of several defects and disadvantages inherent in the construction of prior similar articles.

More specifically, the invention contemplates constructing an improved waistline control garment which is characterized by a ribbed knitted body engaging section having the ribs running vertically and having a waistline with a V-shaped, rounded, or straight cut out at the back for extending along the hollow of the back of a wearer, and having cutout end portions continuing from said V-shaped cut out, or other cutout, and extending along the sides of said body section, and a waistband of novel construction set into said cutouts and attached at its bottom and ends to the edges of the cutouts and adapted to act in a certain manner.

More specifically, the invention proposes that the waistband proper be of one way stretch elastic material stretchable horizontally and of a shape to fit into said V-shaped or other shaped end cutouts of the body engaging section.

Furthermore, the invention contemplates the use of garters mounted upon the bottom edge of the body engaging section at the front and back thereof. The invention further contemplates the use of elastic pieces of two way stretch material stretchable horizontally and vertically, or one way stretch material stretchable vertically only, and mounted on said waistband proper above and in line with said back garters.

The dominating feature of the construction embodying the objects set forth above, resides in the fact that downward pulls on the back garters caused by their attachment to hosiery will be transmitted by the vertical ribs and material of the body engaging section to those portions of the waistband which have the two way stretch elastic pieces, or the one way stretch material, mounted thereon. The waistband proper itself functions to maintain the garment properly fitted on the waistline, and the extra elastic pieces prevent the stresses of the garters which are transmitted up to the waistline from deforming and interfering with action of the waistline band.

Still further the invention contemplates associating the elastic pieces and those areas of the waistband proper beneath the elastic pieces with the adjacent material of the body engaging section in a specific manner so that downward pulls transmitted by the body engaging section will be directly taken by the elastic pieces rather than by the adjacent portions of the waistband proper.

Another object of the invention is the construction of an article as described which is simple and durable and which may be manufactured and sold at a reasonable cost.

2

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an improved 10 waistline control garment constructed in accordance with this invention.

Fig. 2 is a fragmentary enlarged horizontal 15 sectional view taken on the line 2—2 of Fig. 1.

Fig. 3 is a fragmentary vertical sectional perspective view taken on the line 3—3 of Fig. 1.

Fig. 4 is a fragmentary vertical sectional perspective view taken on the line 4—4 of Fig. 1.

Fig. 5 is a fragmentary vertical sectional view taken on the line 5—5 of Fig. 1.

Fig. 6 is a fragmentary perspective view of an 20 improved waistline control garment constructed according to a modified form of the invention.

The improved waistline control garment, in accordance with that form of the invention shown in Figs. 1 to 5 inclusive, includes a ribbed knitted body engaging section 10 having the ribs 11 running vertically and having a waistline 12 with a V-shaped or other shaped cut out 13 at the back for extending along the hollow of the back of a wearer, and said V-shaped cutout being extended 25 at the ends and continuing into end portions 13' extending along the sides to the front of the body section 10. A waistband proper 14 of one way stretch elastic material, stretchable horizontally, as indicated by the double headed arrow 14a, is of a shape to conform with and fit into the V-shaped opening 13 and has end portions fitting into the end cutouts 13'. This waistband proper 14 is secured by a line of stitches 15 extended along most of its bottom edge to the adjacent edge of the cutout 13. Stitches 15' secure the ends of the waistband proper 14 to the material adjacent the ends of the cutouts 13'.

The body engaging section 10 is provided with 30 garters 16 at the back and other garters 16' at the front. The garters 16' at the front are directly below the front central top section of the body engaging section 10, which is located between the end cutouts 13'. The back garters 16 are located directly beneath certain back areas of the waistband proper 14. At these back areas there are elastic pieces 18. These elastic pieces 18 are two-way stretch material, indicated by the two directional arrows 18a. This two way stretch 35 material is arranged to be stretchable horizontally and vertically. The elastic pieces 18 are mounted in a specific manner upon the waistband proper 14.

Each elastic piece 18 is secured at its top edge 40 by a line of stitches 19 to the adjacent top edge

portions of the waistband proper 14. Binding strips 20 and stitches 21 serve to attach both sides of each elastic piece 18 to the adjacent material of the waistband proper 14. The stitches 15 which secure the bottom edge of the waistband proper 14 to the material of the body engaging section 10 are non-existent along the length of the bottom edges of the elastic pieces 18. The bottom edges of the elastic pieces 18 are secured by stitches 22 to the free top edge portion of the free portions of the body engaging sections at the free areas due to the interruption of the stitches 15, see Fig. 3.

In use, the improved waistline control garment functions as follows:

Downward pulls exerted by the hose upon the garters 16 are communicated by the vertical ribs 11 and the material of the body section 10 to the elastic pieces 18 which are mounted on the waistband proper 14. These elastic pieces 18 are capable of stretching vertically to absorb the vertical pulls exerted indirectly by the garters 16. These vertical pulls cannot be transmitted directly to the waistband proper 14 since the top edge portions of the body engaging section 10, which are disposed at the bottom edges of the elastic pieces 18, are connected with the pieces 18 and not with the waistband proper 14. The free portions of the top edges of the body engaging section 10 and the elastic pieces 18 are directly connected by the stitches 22. Horizontal stresses and strains communicated to the waistband 14 by the abdomen are opposed by the horizontal stretch of the waistband itself. The elastic pieces 18, however, are capable of stretching horizontally also so as not to interfere with the horizontal stretch of the waistband 14.

In Fig. 6 a modified form of the invention has been disclosed which distinguishes from the prior form in the construction of the elastic pieces 18x and in the shape of the waistband proper 14x. Each insert 18x is constructed from elastic material stretchable vertically only. In other respects these elastic inserts 18x are associated with the other parts of the waistband proper in the identical fashion as described relative to the elastic inserts 18 in the prior form of the invention, and like parts may be identified by corresponding reference numerals.

The waistband proper 14x distinguishes from the corresponding waistband proper 14 in the prior form of the invention in the fact that it is substantially straight in the back (devoid of the V-shaped formation inherent in the prior form). In other respects its construction and association with the other parts of the garment is identical to the prior form and the corresponding parts may be identified by like reference numerals.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In an improved waistline control garment, a body engaging section having a top edge portion, garters mounted on the bottom of said body engaging section, a waistband proper of one way stretch elastic material stretchable horizontally and set into said top edge portion and stitched thereto along adjacent edges except at restricted areas located vertically above said garters, elastic pieces of one way stretch elastic material stretchable vertically and having top and bottom and side edges and being positioned upon said waistband proper at areas located vertically above said garters, said elastic pieces having their top and side edges stitched to the material of said waistband proper, and said elastic pieces having their bottom edges stitched to said restricted areas of the top edge portion of said body engaging section.

2. In an improved waistline control garment, a body engaging section having a top edge portion, garters mounted on the bottom of said body engaging section, a waistband proper of one way stretch elastic material stretchable horizontally and set into said top edge portion and stitched thereto along adjacent edges except at restricted areas located vertically above said garters, elastic pieces of two way stretch elastic material stretchable vertically and horizontally and having top and bottom and side edges and being positioned upon said waistband proper at areas located vertically above said garters, said elastic pieces having their top and side edges stitched to the material of said waistband proper, and said elastic pieces having their bottom edges stitched to said restricted areas of the top edge portion of said body engaging section.

LOUIS SHULMAN.
